(57) **CLAIM**

The ornamental design for an e-mail notification device, as shown and described.

DESCRIPTION

FIG. 1 is a top and right front perspective view of an e-mail notification device showing our design;

FIG. 2 is a bottom and left rear perspective view thereof;

FIG. 3 is a front elevational view thereof;

FIG. 4 is a rear elevational view thereof;

FIG. 5 is a top plan view thereof;

FIG. 6 is a right side elevational view thereof, the left side elevational view being a mirror image of the side view shown;

FIG. 7 is a bottom plan view thereof;

FIG. 8 is a top and right front perspective view of a second embodiment thereof;

FIG. 9 is a bottom and left rear perspective view thereof;

FIG. 10 is a front elevational view thereof;

FIG. 11 is a rear elevational view thereof;

FIG. 12 is a top plan view thereof;

FIG. 13 is a right side elevational view thereof, the left side elevational view being a mirror image of the side view shown;

FIG. 14 is a bottom plan view thereof; and,

FIG. 15 is a perspective view thereof showing a pivotable stand thereof when in use.

The broken line showing in the figures is for illustrative purposes only and forms no part of the claimed design.
